UNITED STATES PATENT OFFICE.

CHARLES H. CHAPMAN, OF WINCHESTER, MASSACHUSETTS.

BALL-BEARING.

1,123,485.

Specification of Letters Patent.

Patented Jan. 5, 1915.

Application filed September 11, 1913. Serial No. 789,361.

To all whom it may concern:

Be it known that I, CHARLES H. CHAPMAN, a citizen of the United States, residing at Winchester, in the county of Middlesex and State of Massachusetts, have invented a certain new and useful Improvement in Ball-Bearings, of which the following is a full, clear, and exact description.

The object of this invention is to provide 10 a simple and efficient ball bearing, capable of adjustment as desired, and of having such adjustment fixed against liability of derangement incident to use.

The invention consists of a ball bearing 15 in which the balls are arranged in a ball-race made up of concentrically arranged parts, one of which is adjustable and capable of having its adjustment fixed, as I will proceed now more particularly to explain 20 and finally claim.

In the accompanying drawings illustrating the invention, in the several figures of which like parts are similarly designated, Figure 1 is an elevation, with a quarter-section 25 in section. Fig. 2 is a view at right angles to Fig. 1, enlarged. Fig. 3 is an elevation of the locking spring detached, and Fig. 4 is an edge view thereof. Fig. 5 is a side view and quarter-section of the cone 30 forming the inner member of the ball-race.

The so-called "cone" 1 may be a ring of suitable shape, having the circumferential groove 2. This cone forms the inner or central member of the ball-race. The outer 35 member of the ball-race consists of what is termed the stationary cup 3, an adjustable cup 4, having, respectively, the grooves 5 and 6, which are complementary to the groove 2 in the inner cone 1, and a ring 40 housing 7 in which the cup members 3 and 4 are mounted and supported concentrically with relation to the cone. The stationary cup 3 has the beveled back 8 to match a complementary part 9 in the inside of the ring 45 housing, whereby it is properly held in place and in perfect alinement with the adjustable cup 4. It is a well known fact that a cup screwthreaded and adapted to be screwed into a screwthreaded housing will, 50 when screwed in or out, change its alinement with relation to a stationary and fixed cup, on account of the variation existing in the threads of either the cup or the housing. In my invention the cup 3 is supported entirely 55 by its beveled back 8 and the beveled portion 9 of the housing. The outside

diameter of the cup 3, in practice, has an easy slip fit in the housing, so that the stationary cup 3 automatically conforms in its alinement, by the pressure of the balls, to 60 the adjustable cup 4 at all times, thereby enabling the production of a practically perfect ball race. This alinement or adjustability of the stationary cup is obtained by virtue of the narrow width of the beveled 65 portion of the cup, in proportion to the diameter of the cup, and the location of the points of contact of the balls within the cup, so that a slight variation of a few thousandths of an inch (which is barely 70 perceptible) is effected and is sufficient to obtain the desired results.

Beyond the cup 3 the interior of the housing is screwthreaded, as at 10, and in this portion is arranged the adjustable cup 75 4. Any suitable means may be employed for turning the cup 4 into the ring housing, and I have shown one such in the lateral projections or pins 11 on the cup and the hole 12 in the housing, to receive suitable spanner 80 wrenches.

The housing is provided with a groove 13 next to the adjustable cup 4, and the bottom of this groove is provided with suitable retaining means, such as fine serrations, or 85 corrugations, or the like, as indicated at 14, Fig. 2; and there is provided a rim-flange 15 overhanging this groove vertically.

16 is an unbroken ring, of spring metal, transversely bowed as indicated in Fig. 4. 90 This ring has the projection 17 whose rim is serrated or otherwise prepared, as at 18, to match the bottom construction of the groove 13; and it is also provided with the slot 19 to engage one of the pins 11. Dia- 95 metrically opposite these parts are the projections 20 separated by the notch 21, and the slot 22 to engage the opposite pin 11. When the cup 4 is screwed in place in the housing, the ring 16 is sprung into the 100 groove 13, convex side inward with its serrated part 18 in engagement with the serrations of the groove and its opposite projections 20 also in engagement with said groove and its slots 19 and 22 in engagement with 105 the pins 11, so that the cup 4 will be locked against turning in or out. The notch 21 will admit a screw-driver or other blade to remove the ring when desired. It is not necessary to serrate the projections 20. 110

It is to be observed that the groove 13 extends entirely around the housing, and that

the spring ring may be snapped in at any part thereof so as to engage the pins 11 wherever they may be set by the adjustment of the cup 4. By the present means of adjusting and locking or fixing such adjustment, it is possible to adjust the bearing to less than one ten-thousandth of an inch, and to fix it without disturbing or in any way altering the adjustment.

10 Any suitable arrangement of balls may be used; the preferred being shown in the drawings, and comprising load-carrying balls 23 separated by tubular floats 24 within which are the idler balls 25 of smaller diameter than the balls 23 but in contact with them. These idler balls are located upon lines passing through their centers and the centers of the load-carrying balls on either side, and they serve to prevent cross-friction of the 15 load-carrying balls, and also act as friction drivers to insure the positive revolution of the load-carrying balls. These balls and their floats are arranged in the ball-race formed by the cone and the cups and held 20 therein by properly adjusting the cup 4 in the housing and fixing such adjustment by the spring ring 16. It will be observed that the ball-race is uninterrupted.

25 The cone and the cups are preferably made of high-grade steel, hardened and tempered to obtain both strength and great wearing qualities, after which they are ground to perfect measurement.

30 The ring 16 preferably is of steel, hardened and spring tempered. When this ring is sprung into place in the groove in the housing it tends on account of its bowed form to lie flat on the cup 4.

35 Variations of structure are deemed to be 40 within the scope of the invention as herein claimed.

What I claim is:—

1. A ball bearing, having a grooved cone, a stationary alinable cup, an adjustable cup, 45 and a grooved housing uniting the cups and with the cone forming an uninterrupted ball-race, balls arranged in said ball-race, and means to adjust the same, an unbroken, independent, bowed spring ring adapted to 50 engage the groove in said housing and the adjustable cup and lock the same against displacement.

2. A ball-bearing, comprising a cone, a housing, ball cups within said housing, one 55 of which ball cups is adjustable within the housing and the other stationary and adapted to aline itself automatically with the adjustable cup, said cone and ball cups forming an uninterrupted ball-race, balls within 60 said ball-race, and an unbroken, independent, bowed spring ring adapted to engage

the housing and the adjustable cup and lock the adjustment against displacement.

3. A ball bearing, comprising a cone, a housing, ball cups within said housing, one 65 of which ball cups is adjustable within the housing, these members forming an uninterrupted ball-race, balls within said ball-race, said housing having an interior groove serrated in its bottom and provided with an external flange, and an unbroken, bowed spring ring sprung into said groove and provided with serrations to engage those in the groove, and means to interlock the spring ring and the adjustable cup. 70

4. A ball bearing, comprising a cone, a housing, ball cups within said housing, one of which ball cups is adjustable within the housing and the other stationary and adapted to aline itself automatically with the adjustable cup, these members forming an uninterrupted ball-race, balls within said ball-race, the housing having an interior groove provided with retaining means, and the adjustable cup having exterior lateral projections, and an unbroken bowed spring ring sprung into said groove and engaging the retaining means therein and provided with slots to engage the lateral projections on said adjustable cup to hold the adjustable 80 cup in given position.

5. A ball bearing, having a ball-race made up of a grooved cone, a housing screw-threaded at front and provided with an interiorly beveled back, a ball cup complementally beveled and fitted against the beveled back and self-alignable in said housing, an adjustable ball cup movably fitted in the screwthread, and means engaging the housing and adjustable cup to interlock them. 95

6. A ball bearing, having a ball-race made up of a cone, cup members, and a housing which receives and supports the cup members, the housing having a groove, and a ring having opposite projections to engage 105 the groove in the housing, the projection at one point being notched to receive a detaching tool.

7. In a ball bearing, a housing having a corrugated inside groove, an adjustable ball 110 cup in said housing, and a transversely bowed spring metal ring adapted to engage such groove and said adjustable cup to lock the cup against displacement.

In testimony whereof I have hereunto set 115 my hand this ninth day of September A. D. 1913.

CHARLES H. CHAPMAN.
